UNITED STATES PATENT OFFICE.

BARNEY ZINDEL, OF GREEN BAY, WISCONSIN.

SAFETY-GATE FOR BRIDGES.

1,364,421.

Specification of Letters Patent.

Patented Jan. 4, 1921.

Application filed May 20, 1920. Serial No. 382,895.

To all whom it may concern:

Be it known that I, BARNEY ZINDEL, a citizen of the United States, residing at Green Bay, in the county of Brown and State of Wisconsin, have invented certain new and useful Improvements in Safety-Gates for Bridges; and I do declare the following to be a full, clear, and exact description of the invention, such as will enable others skilled 5 in the art to which it appertains to make and use the same.

This invention relates to an improved safety gate for use in connection with a bridge having a section which may be swung 15 to a raised position and one object of the invention is to provide an improved operating means for the safety gate so that when the movable section or draw is swung to a raised position, the safety gate will be lowered 20 and thus prevent danger of accidents.

Another object of the invention is to so construct this operating mechanism that opening of the draw will cause the gate to swing to a lowered position and closing of 25 the draw will cause the gate to swing to a raised position.

Another object of the invention is to so construct this operating mechanism that gates upon both sides of a bridge may be 30 simultaneously operated and to further so construct the operating mechanism that rotation of the main shaft may be limited and abutment means provided constituting yieldable bumpers.

35 This invention is illustrated in the accompanying drawings wherein—

Figure 1 is a view showing a bridge in longitudinal section with the safety gate in a raised position and the draw or movable 40 bridge section in a lowered or closed position.

Fig. 2 is a transverse sectional view through a bridge showing the safety gate at one end of the draw in a lowered position, 45 the gates and operating mechanism being disclosed in elevation.

Fig. 3 is an enlarged view in elevation showing the balance wheel and bumper means forming part of the operating mechanism.

50 Fig. 4 is an enlarged view showing a portion of one of the gates in longitudinal and horizontal section.

Fig. 5 is a view showing the structure of 55 Fig. 4 partially in elevation and partially in section.

These gates will be used in connection with a bridge indicated in general by the numeral 1 and having a movable section or draw 2 which will be constructed and mounted in the usual manner for swinging vertically to an open position. The means for mounting and swinging the section 2 is of a conventional construction and is indicated by the numeral 3. These gates will be mounted 60 upon the bridge at opposite ends of the movable section 2 and in spaced relation to the movable section and will be mounted to extend transversely of the bridge when in a lowered position as shown in Fig. 2 thus 65 shutting off the bridge to the draw and preventing danger of vehicles running into an open draw. The gates at the opposite ends of the draw will have a duplicate construction and the operating mechanism will be 70 similar in construction except for a change hereinafter noted and therefore a description of one will suffice for both sets.

These gates are erected upon opposite sides of the bridge as shown in Fig. 2 and 75 each gate is provided with a base 4 having spaced side bars or arms 5 which carry a shaft 6 upon which the main gate 7 is mounted for vertical swinging movement. This main gate carries the auxiliary gate 8 80 which is pivotally connected with the main gate through the medium of a shaft 9 and this shaft 9 carries a gear wheel or pinion 10 which meshes with an idler gearing 11 rotatably connected with the main gate as 85 shown in Fig. 5. The gear or pinion 11 in addition to meshing with the gear 10 meshes with a large gear 12 secured to the base 4 about the shaft 6 and as the main gate 7 swings the idler gear 11 will be rotated and 90 rotary movement will be transmitted to the shaft 9 thus causing the auxiliary gate 8 to 95 swing upwardly and downwardly with the main gate. It will thus be seen that as the main gate swings into and out of position to extend across the vehicle and car section of a bridge, the auxiliary gate will, at the same time, move into and out of position to extend across the sidewalk section of the bridge.

100 A rocker shaft 13 is rotatably mounted beneath the bridge and is provided with crank arm extensions 14 from which extend links 15 having connection with the levers 16 of the shafts 6 for the two sets of gates 110 as shown in Fig. 2 and it will thus be seen that when this rocker shaft 13 is rotated,

rotary movement will be imparted to the driving shafts of the two gates and the gates will be swung to a raised or a lowered position according to the direction in which the 5 shaft 13 rotates. In order to normally retain the gates in a lowered position and cause the gates to be moved to a lowered position when the draw is opened, there has been provided a spring 17 which will be anchored as shown at 18 and have its opposite end connected with a lever arm 19 extending from the shaft 13. It is of course understood that if desired a number of lever arms 19 will be provided and a spring connected 10 with each arm in order to increase the power and permit the gates to be easily swung to a lowered position. A draw bar 20 is connected with this lever arm 19 and is connected with a rocker lever 21 by means of a 15 spring 22 carried by the lever 21 and a turn buckle 23 connected with the spring for free rotation and screwed upon the threaded end portion 24 of the draw bar 20. This rocker lever 21 is extended upwardly and connected 20 with a plunger 25 which extends through a guide 26 and terminates in an enlarged head 27 constituting an abutment and a cam head for engagement by the similarly shaped head 28 of an abutment 29 carried by the 25 bridge. It will thus be seen that when the bridge is in the closed position the abutment 29 through engagement with the head of the plunger will lock the lever 21 and draw upon the draw bar 20 thus rotating the 30 shaft 13 and swinging the gates to a raised position against the action of the spring 17. When the draw is swung to the raised or open position the pressure is removed from the plunger 25 and the spring 17 will then act 35 upon the lever 19 to rotate the shaft 13 and draw the gates down to a lowered position where they will extend across the bridge and 40 shut off traffic.

The structure shown at the right hand 45 portion of Fig. 1 is similar to that shown at the left hand portion except that the lever 19 is connected with a rocker bar 30 which extends horizontally or longitudinally of the bridge, the arm 19 being connected with 50 this lever 30 through the medium of a spring 31. This lever 30 has its free end extending beyond the end of the stationary bridge section and terminates in a head 32 which resembles the head of a treadle and is engaged by an abutment 33 carried adjacent 55 the end of the draw 2. This abutment 33 engages the head of the lever as the draw swings downwardly to the lowered or closed position and moves the lever 30 to draw upon 60 the lever 19 and swing the safety nose to a raised position against the action of the spring 17. It will thus be seen that the gates at the opposite ends of the draw operate upon the same principle but are provided with a specific construction which is 65

slightly different, this being necessary as the two end portions of the vertically swinging draw engage the stationary sections of the bridge from different directions.

It is desired to eliminate jolts and sudden 70 stops as the safety gates move to a raised or a lowered position and in order to do so the shaft 13 has been provided with a balance wheel 34 which permits the shaft 13 to rotate easily. This balance wheel carries 75 a counterbalancing weight 35 which extends circumferentially of the wheel to one side thereof and has its end portions provided with outstanding lips 36 for engaging the abutment bar 37. This bar 37 extends radially of the wheel 34 as shown clearly in Fig. 3 and is suspended by rods 38 which extend through openings in the supporting beams 39 of the bridge and carry abutment nuts 40 engaging the springs 41. When the 80 shaft 13 rotates to swing the gates from one position to another the bar will be engaged by one end of the counter balancing trip 35 and this will limit rotation of the shaft 13 and permit the rotation of the shaft to be 85 stopped without any sudden jar.

What is claimed is:

1. The combination with a bridge having a stationary section and a movable section, of a safety gate movably mounted for extending across the stationary section of the bridge when the movable section is open and including a rotatably mounted rocker shaft, a rocker shaft rotatably connected with the stationary section of the bridge and having 95 connection with the rocker shaft of the gate for imparting rotary movement to the rocker shaft of the gate when the rocker shaft of the bridge rotates, an arm extending from the rocker shaft of the bridge, resilient means engaging the arm to yieldably hold the rocker shaft against rotation with the gate lowered, a rocker lever pivotally connected with the stationary section of the bridge, a pitman connecting said arm with 100 one end of said lever, and a plunger connected with the second end of the lever and extending for engagement by an abutment carried by the movable bridge section to impart movement against the action of the resilient means and raising the gate when the 105 movable bridge section is closed.

2. The combination with a bridge having a stationary section and a movable section, of a safety gate movably mounted for extending across the stationary section of the bridge when the movable section is open and including a rotatably mounted rocker shaft, a rocker shaft rotatably connected with the stationary section of the bridge and having 110 connection with the rocker shaft of the gate for imparting rotary movement to the rocker shaft of the gate when the rocker shaft of the bridge rotates, an arm extending from the rocker shaft of the bridge, re- 115

silient means engaging the arm to yieldably hold the rocker shaft against rotation with the gate lowered, a rocker lever pivotally connected with the stationary section of the 5 bridge, a pitman connecting said arm with one end of said lever and said lever extending for engagement by the movable bridge section and imparting rotary movement to the shaft of the bridge and raising the gate 10 when the movable bridge section is moved to a closed position and engages the lever.

3. A safety gate comprising a support, a rocker shaft carried by the support, a main gate pivotally mounted by said shaft, a gear 15 rigidly connected with the support about said shaft, an auxiliary gate, a pivot shaft connecting the auxiliary gate with the main gate for vertical swinging movement, a gear rigidly carried by the pivot shaft, a gear 20 rotatably connected with the main gate and having engagement with the first and second mentioned gears for imparting rotary movement to the pivot shaft as the main

gate swings vertically, and means for rotating the rocker shaft and swinging the 25 main gate.

4. A safety gate comprising a support, a main gate pivotally connected with the support, an auxiliary gate pivotally connected with the main gate for vertical swinging 30 movement, a driving gear rigidly connected with the support, the auxiliary gate having a pivot shaft journaled in the main gate to pivotally connect the auxiliary gate with the main gate, a gear rigidly connected with 35 the pivot shaft of the auxiliary gate and a gear rotatably connected with the main gate and engage the first and second mentioned gears and impart rotary movement to the pivot shaft of the auxiliary gate and raise 40 and lower the auxiliary gate with the main gate.

In testimony whereof I have hereunto set my hand.

BARNEY ZINDEL.
